BIB

Bess Kaye, New York, N. Y.

Application November 20, 1957, Serial No. 48,561

Term of patent 7 years

(Cl. D3—26)

Fig. 1 is a front elevational view of a bib, showing my new design;

Fig. 2 is a sectional view taken on the line 2—2 of Fig. 1; and,

Fig. 3 is a rear elevational view of Fig. 1.

The characteristic feature of my design resides in the combination on the bib disclosed of the specific figure applied to the front as shown.

I claim:

The ornamental design for a bib, substantially as shown and described.
